UNITED STATES PATENT OFFICE.

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY.

MACHINE FOR SEWING ROUND-EYE BUTTONHOLES.

Application filed January 9, 1924. Serial No. 685,101.

To all whom it may concern:

Be it known that I, EDWARD B. ALLEN, a citizen of the United States, residing at Newtown, in the county of Fairfield and 5 State of Connecticut, have invented certain new and useful Improvements in Machines for Sewing Round-Eye Buttonholes, of which the following is a specification, reference being had therein to the accompanying 10 drawings.

This invention has for an object to provide a buttonhole sewing machine for sewing round eye buttonholes with an overseam of substantially uniform width and appearance.

15 Buttonhole sewing machines are commonly constructed with a stitch-forming mechanism and a work-holder with provision for relative movement between them to carry the sewing around the buttonhole-slit. 20 In cloth buttonhole machines the stitch-forming mechanism usually comprises an upper reciprocating and laterally jogging needle which cooperates with suitable under-thread mechanism mounted in a rotary turret. 25 The needle-bar and turret are connected for turning movements in sewing around the eye of the buttonhole.

Heretofore it has been the practice to hold the turret of the stitch-forming mechanism 30 in a fixed position with the plane of vibration of the needle normal to the center line or stem of the buttonhole slit as the sewing progresses along the first side of the buttonhole and the first quarter of the eye; i. e., 35 until the sewing has reached a point even with the center of the circular part of the eye. The stitch-forming mechanism is then rotated 180° as the stitches are laid around the semi-circular second and third quarters 40 of the eye. Rotation of the stitch-forming mechanism is then stopped with the plane of vibration of the needle again normal to the center line of the buttonhole as the sewing progresses along the last quarter of the eye. 45 and down the return side of the buttonhole. In other words buttonholes sewn by machines of the prior art have had the stitches laid substantially normal to the center line of the buttonhole along the stem of the buttonhole-slit and the first and last quarters 50 of the eye. Buttonholes having elongated pear-shaped eyes may be satisfactorily sewn in accordance with the practice above outlined while retaining a substantially uni-

form width of overseam. At least the departure from normal width of overseam is not objectionable along the first and last quarters of the eye. In attempting to shorten the eye of the buttonhole, however, and make it more nearly circular and less 60 pear-shaped, as often demanded by the trade, it is found that the effective width of the overseam along the first and last quarters of the eye, as sewn in accordance with the customary practice, is so reduced as to contrast unfavorably with the width of the overseam along the buttonhole-slit and around the second and third quarters of the eye.

According to the present improvement, 70 as the sewing starts, the plane of vibration of the needle stands normal to the center line of the buttonhole, as heretofore, but provision is made for reversely rotating the stitch-forming mechanism as the sewing approaches the eye of the buttonhole so that when the eye is reached the plane of vibration of the needle stands at such an angle to the center-line of the buttonhole that the initial eye-strokes will be laid more nearly 75 normal to the underlying edge of the eye instead of normal to the center line of the buttonhole, as heretofore. As soon as the initial eye-forming stitches are laid the stitch-forming mechanism is rotated in the 80 usual direction but for double the angle in excess of 180° that the stitch-forming mechanism was initially reversely rotated. After the final eye-forming stitches are laid the stitch-forming mechanism is reversely 85 rotated during the sewing along the return side of the buttonhole until the plane of vibration of the needle again stands normal to the buttonhole-slit. By reversely rotating the stitch-forming mechanism, as above 90 pointed out, the spacing of the depth stitches will be reduced along the stem portions of the overseam adjacent the initial and final eye-strokes. The effect of this reduction in spacing of the depth-strokes is to bunch 95 such stitches at the apex of the angle where the stem and eye stitches meet, thereby forming strong anchorages at these points for holding sharp bends in the cord and thus accentuating the desired circular appearance of the eye. After the sewing is completed, the stitch-forming mechanism is or may be reversely rotated 180° to restore 100 105

it to initial position ready for the next sewing operation.

In the accompanying drawings, Fig. 1 is a fragmentary perspective view of a button-hole sewing machine embodying the invention. Fig. 2 is a fragmentary bottom plan view of the machine. Fig. 3 is a diagrammatic view of the eye end of a buttonhole having the usual pear-shaped eye. Fig. 4 is a similar view of a round eye buttonhole produced in accordance with the usual practice of laying the eye stitches. Fig. 5 is a diagrammatic view of a round eye buttonhole produced in accordance with the present invention and Fig. 6 is a face view of the corded face of the buttonhole illustrated in Fig. 5.

In the embodiment of the invention illustrated, 1 represents the frame bed of a buttonhole sewing machine which, except as hereinafter specified, preferably embodies the constructive features disclosed in my Patent No. 15,324, reissued April 4, 1922. Rising from the bed 1 is the standard 2 of the overhanging bracket-arm 3 which terminates in the head 4.

The stitch-forming instrumentalities comprise the reciprocating and laterally jogging needle 5 and under thread-looping devices 6 preferably constructed substantially in accordance with the disclosure of the Allen & Faulkner Patent No. 1,372,473, of March 22, 1921. The needle 5 is mounted as usual in the block 7 which jogs laterally 30 on the horizontal supporting pin 8 carried by the needle-bar 9 mounted in the head 4 for endwise reciprocatory and axial turning movements; the latter being derived from the sector-gear 10 which meshes with the pinion 11 coaxially connected with the needle-bar. The under thread-looping devices 6 are carried by the turret 12 which derives turning movements from the sector-gear 13 meshing with the pinion 14 coaxially 40 connected to the turret. 45

The sector-gears 10, 13, are connected to be turned in unison by means of the links 15, 16, which are joined to the upper and lower arms 17, 18, mounted rigidly on the vertical shaft 19. The lower arm 18 carries a cam-follower roll 20 which enters the cam-groove 21 in the feed-wheel 22.

The cam-groove 21 is specially formed to impart reverse turning movements to the stitch-forming mechanism immediately prior and subsequent to the eye-stitching operation and to this end has the usual concentric portion, between the points 23 and 24, Fig. 2, which holds the stitch-forming mechanism with the plane of vibration of the needle normal to the buttonhole-slit while the sewing proceeds down the first side of the buttonhole. From the point 24 to the point 25 the cam-groove recedes from the center *c* of the feed-wheel to impart the ini-

5 tial reverse turning movement to the stitch-forming mechanism as the sewing approaches the eye of the buttonhole. The eye-sewing begins as the point 25 engages the follower roll 20 and from the point 25 to the point 26 the cam-groove 21 approaches the center *c*, and turns the stitch-forming mechanism in the normal direction as the sewing proceeds around the edge of the buttonhole. From the point 26 to the point 27 the cam-groove 21 again recedes from the center *c* and imparts a reverse turning movement to the stitch-forming mechanism following the eye-sewing operation. From the point 27 to the point 28 the cam-groove 21 is concentric and holds the stitch-forming mechanism with the plane of vibration of the needle normal to the buttonhole-slit as the sewing continues to the end of the second side of the buttonhole. From the point 28 to the starting point 23 the cam-groove 21 recedes from the center *c* and imparts a reverse turning movement to the stitch-forming mechanism after the sewing is completed, to restore the parts to initial position ready for the next buttonhole sewing operation.

It will be understood that the machine is or may be equipped with the usual work-holder, indicated generally at 29, which slides longitudinally of the bed 1 and is actuated from the feed-wheel 22 through the usual connections.

Referring to Fig. 3, which illustrates diagrammatically the upper or needle-thread side of the usual pear-shaped eye-end of a buttonhole, it will be seen that the dot-and-dash lines which represent the plane of vibration of the needle stand normal to the center line of the buttonhole as the sewing proceeds in the direction of the arrows around the first and last quarters of the eye. This is in accordance with the customary practice. It will be seen that with the extent of vibration of the needle maintained constant, the width of the overseam around the first and last quarters of the eye is not noticeably or objectionably narrowed as compared to the width of the overseam along the stem or around the second and third quarters of the eye.

When the length of the eye, however, is reduced and made more nearly circular and less pear-shaped, as shown in Fig. 4, the width of the overseam around the first and last quarters of the eye is noticeably reduced and contrasts unfavorably with the overseamed portions along the stem and around the second and third quarters of the eye, giving the eye as a whole a distorted appearance.

In accordance with the present improvement, Fig. 5, the plane of vibration of the needle stands normal to the center line of the buttonhole from the beginning point 30

along the major portion of the first side of the buttonhole and until the sewing reaches the point *a* close to the eye. From *a* to *b* the stitch-forming mechanism is gradually 5 reversely turned through an angle of say 24° so that when the eye is reached the plane of vibration of the needle will stand more nearly normal to the edge of the eye at the first quarter of the eye of the buttonhole, in- 10 stead of normal to the center line of the buttonhole, as heretofore. The angular position of the stitch-forming mechanism is retained in sewing from *b* to *d* and then the stitch-forming mechanism is rotated in 15 the normal direction, in sewing around the eye from *d* to *e*, but through an angle of 180° plus double the angle 24° of initial reverse rotation, or 228° in all. From *e* to *f* the angular position of the stitch-forming 20 mechanism is retained and from *f* to *g* the stitch-forming mechanism is again reversely rotated through an angle of 24° to bring the plane of vibration of the needle again normal to the center line of the buttonhole 25 for sewing along the remaining and major portion of the second side of the buttonhole to the ending point *t*.

By providing a buttonhole sewing machine with means for reversely rotating the 30 stitch-forming mechanism in the manner described, the eye of the buttonhole is given a uniformly overseamed appearance and is of the desired circular shape. The depth stitches from *a* to *b* and *f* to *g* and particularly at the points *b* and *f* are crowded together, Figs. 5 and 6, and form firm anchorage around which the cord *h* is sharply bent to accentuate the desired circular appearance of the eye. It will be understood that 35 the angular amount of reverse rotation of the stitch-forming mechanism is not critical and that the preferred amount is specified herein in an illustrative and not a limiting sense.

40 The buttonhole produced by the machine may be characterized as including an over-seam embracing the cord *h* on one face of the fabric and having a needle thread disposed in zigzag arrangement on the other face of the fabric. From the point *s* to the point *a*, Fig. 5, the sum of the inner angles *s'* minus the sum of the outer angles *s²* is 45 zero since the stitch-forming mechanism is not rotated in sewing the major portion of the stem of the buttonhole. From *a* to *b*

the sum of the inner angles *a'* minus the sum of the outer angles *a²* is a negative angle of 24° since the stitch-forming mechanism is reversely or negatively rotated through an angle of 24° in sewing the stem stitches immediately adjacent the eye. From *b* to *d* there is no rotation of the stitch-forming mechanism and the difference of the sums of the inner and outer angles is again zero. From *d* to *e* the sum of the inner angles *d'* minus the sum of the outer angles *d²* is a positive angle of 228° , and so on to the point *t*, as will be readily understood. The stem end of the buttonhole may, of course, be finished off 50 or barred in any desired manner.

Having thus set forth the nature of the invention, what I claim herein is:—

1. An eyelet-end buttonhole sewing machine having stitch-forming mechanism and a work-holder with means for relatively rotating the stitch-forming mechanism and work-holder in sewing around the eye-end of a buttonhole and for reversely relatively rotating the stitch-forming mechanism and work-holder in sewing the side stitches immediately adjacent the eye-strokes. 75

2. An eyelet-end buttonhole sewing machine having a work-holder and rotary stitch-forming mechanism including means 85 for rotating the stitch-forming mechanism in sewing around the eye-end of a button-hole and for reversely rotating the stitch-forming mechanism immediately prior and subsequent to the eye-sewing operation and 90 while sewing the side stitches immediately adjacent the eye-strokes.

3. An eyelet-end buttonhole sewing machine having a work-holder and rotary stitch-forming mechanism including means 95 for rotating the stitch-forming mechanism in sewing around the eye-end of a button-hole and for reversely rotating the stitch-forming mechanism immediately prior and subsequent to the eye-sewing operation and 100 while sewing the side stitches immediately adjacent the eye-strokes, the angle of rotation of the stitch-forming mechanism in sewing around the eye being substantially 180° plus the sum of the angles of reverse 105 rotation given the stitch-forming mechanism while sewing said side stitches.

In testimony whereof, I have signed my name to this specification.

EDWARD B. ALLEN.
